METHOD OF MAKING ROUND BRUSHES

William C. Leete, Longmeadow, Mass.

Application May 8, 1948, Serial No. 25,893

3 Claims. (Cl. 300—21)

1

This invention relates to a method of making a round brush of the type used in hydraulic brush devices. Such devices are generally used for washing and cleansing automobiles, busses, train coaches, and surfaces such as windows, decks, floors, or for other purposes of analogous nature. The devices may be hydraulically or electrically driven as in a rotary type or the brush may be of a non-rotary type, all as is well known in the art.

The method of the present invention is particularly useful in making a brush of good quality, formed in a manner as to permit ready passage of water through the brush and to diffuse and apply the water directly where required, continuously and uniformly, and to make such a brush at much less than the usual cost of round brushes used heretofore in devices of this nature.

In the drawings:

Fig. 1 is a diagrammatic view of an apparatus used in the practice of this method;

Fig. 2 is a plan view of a portion of Fig. 1;

Fig. 3 is a side elevation of the brush product;

Fig. 4 is a sectional view of a brushholder; and

Fig. 5 is a view on line 5—5 of Fig. 3.

An example for practicing the new method will be seen from considering these figures.

Strips 1 and 2 (Fig. 1) of rubber stripping material or other suitable backing material impervious to water and approximately two inches in width, are fed from stock feed reels 3 and 4. Strip 1 from feed reel 3 passes under a hold-down roll 5 and over a coating roll 6, the latter being partially immersed and rotatable in a tank 7 filled with latex or rubber cement or other suitable adhesive substance. The strip is then passed under a second hold-down roll 8 to the bight of squeeze rolls 9 where it converges with strip 2 being fed from reel 4.

A hopper 10 is filled with bundles 11 of bristles, the bundles being approximately twelve inches in length in the present example. The bundles 11 are dropped singly from the hopper in the path of a spring pressed plunger 12 of a reciprocating device 12 which inserts a bundle at spaced intervals into the bight of squeeze rolls 9 and crosswise between the two continuously fed backing strips 1 and 2. The backing strips centrally encompass each bundle of bristles passing between squeeze rolls 9. The latex or rubber cement on strip 1 spreads among the bristles and bonds each bundle 11 to the two strips to form a series of spaced bundles with

strips 1 and 2 being laminated by the adhesive in the intervening spaces between bundles. A continuous laminated strip is thus formed with spaced bundles of bristles held in it.

Backing strips 1 and 2 are disposed about the middle of the bundles 11 and the continuous laminated strip with its spaced bundles (Fig. 2) is fed centrally against a slitter knife 13 which splits it in half. Pressure rolls 14 and 15 (Fig.

10) guide the strip past the slitter knife 13. Additional squeeze rolls 16 are provided to further solidify the now two separate strips 17 and 18 squeezing out a bead of latex at the severed inner ends to be later used for bonding purposes. The severed halves 17 and 18 of the strip are coated with an adhesive, as latex or rubber cement, on their bottom surfaces (as in Fig. 1) as by passing them over a coating roll 19, partially immersed and rotatable in adhesive tank 20.

Strips 17 and 18 are then turned in opposite directions and twisted by rolls 21 so that the free ends of the bristles will be disposed upwardly. This provides two "winding tapes" each of which is guided by guide rolls 22 to a spindle 23 (Fig. 4) in a brush backing holder 24. The tape is then wound around the spindle so that a round brush is spirally built up on a backing form. The end of each strip as tape 17 and 18 is hooked or otherwise held in one of the slots 25 in spindle 23 and the holders rotated to cause the strips to wind around the spindle. Each strip, being tacky from the latex or rubber cement coating, bonds together in spiral form.

It will be especially noted that the bulges made by the bristle tufts or bundles as they are wound on the spindle will space the strips concentrically in more or less honey comb manner to permit the flow of water throughout the entire bristle area of the brush (Fig. 5).

The latex or rubber cement coated on strips 17 and 18 by coating roll 19 will adhere and bond the peripheral winding to the sides of the holders and the excess bead of latex or cement squeezed out by rolls 16 will bond the bristles and the strips to the bottoms of the holders.

When holders 24 are filled, the strips are cut and end portions tucked in. The brush assembly (Fig. 3) may then be lowered, holder end first, into latex or suitable adhesive to a depth of approximately one fourth inch above the top of the holder 24 to bond all parts. This additional sealing of the brush into the backing holder may be accomplished, of course, in any other suitable manner.

The resulting product, when the adhesive has

set, is a brush which will be continuously flushed by water entering through inlet of spindle 23 (Fig. 4) to carry away dirt loosened by the brush action.

The water is spread throughout the base of the brush by permitting water to pass through holes 26 in the sides of the spindle to a circular cavity 27 in the base of the holder. Holes 28 in the bottom thereof thus diffuse the water throughout the entire brush area.

I claim:

1. The method of forming a round brush which comprises coating one side of a strip of backing material with an adhesive substance, bringing said coated strip in contact with a second strip with the adhesive between the two strips, squeezing the strips together while intermittently feeding crosswise between them and centrally encompassing preformed undivided bundles of bristles of greater length than the strip width to form a continuous laminated strip of backing material with spaced bundles of bristles bonded therein and the free end portions thereof extending from opposite sides of said strip, severing said laminated strip longitudinally, winding each strip half on the spindle of a circular backing form, severing a strip when the form is full, and adding additional adhesive in the backing form to bind the assembled brush firmly in its backing.

2. The method of forming a round brush which comprises coating one side of a strip of backing material with an adhesive substance, bringing said coated strip in contact with a second strip with the adhesive between the two strips, squeezing the strips together while intermittently feeding crosswise between them undivided bundles of bristles of greater length than the width of the strip to form a continuous laminated strip of backing material with spaced bundles of bristles bonded therein, splitting said laminated strip and bundles held therein centrally of the strip to form two similar continuous strips, winding said two strips on spindles of backing forms, disposing the unattached ends of the bristles outwardly of said forms, severing each of the strips when the back-

ing forms are full, and adding adhesive directly to each backing form to bind the brush so assembled therein firmly to the form.

3. The method of forming a round brush in a circular backing form provided with a centrally disposed spindle construction, which method consists in coating one side of a strip of backing material with an adhesive impervious to water, bringing said strip together longitudinally with a strip of similar material and with the coated side of said first strip facing the second, progressively squeezing the two strips together while successively inserting crosswise and centrally squeezing between them at the point of contact of said strips preformed undivided bundles of bristles of greater width than said strips, slitting the resulting laminated strip to form two tapes with unattached bristle ends extending from the outer edge thereof, squeezing said tapes adjacent their inner edges to further bond the bundles of bristles in the tape and press some adhesive from the severed bristle ends, adhesively coating one side of each tape, turning the same edgewise for upward disposal of the unattached bristle ends, fixing the loose end of each tape to the spindle of the backing form, turning said spindle to wind said tape spirally in the form, severing the tape when the form is full, and adding adhesive to the backing form and tape to bind the assembled brush in the form.
